(57) **CLAIM**

The ornamental design for a shopping trolley, as shown and described.

DESCRIPTION

FIG. 1 is a front view of the first shopping trolley; FIG. 2 is a right side view of the shopping trolley of FIG. 1; FIG. 3 is a left side view of the shopping trolley of FIG. 1; FIG. 4 is a back view of the shopping trolley of FIG. 1; FIG. 5 is a top view of the shopping trolley of FIG. 1; FIG. 6 is a bottom view of the shopping trolley of FIG. 1; and,

FIG. 7 is a perspective view of the shopping trolley of FIG. 1.

It is to be understood that the stylized text in FIGS. 1 and 7, the rectangular sticker with rounded edges shown in FIG. 5, the rectangular plate with text, and the indicia shown in FIG. 4 are for illustrative purposes only and form no part of the claimed design.
